Filed Mar. 31, 1958, Ser. No. 725,163
11 Claims. (Cl. 323—22)

This invention relates to voltage regulating means, and more particularly to voltage regulators for regulating a source of relatively low voltage and for providing a regulated low voltage, high current, low impedance power supply. The voltage regulator circuits of the present invention are particularly useful for regulating the voltage source available in an automobile so that it may be applied to a portable transistorized television receiver, and the like.

The battery in a vehicle, such as an automobile, would usually be receiving a charge while the vehicle is in operation. Changing the speed of the vehicle, for example, usually results in changing the charging rate of the battery. While the voltage regulators supplied with most vehicles are adequate for the purposes originally intended, they do not provide a sufficiently regulated voltage to operate a portable transistorized television receiver satisfactorily.

Accordingly, it is an object of the present invention to provide an improved voltage regulator adapted to regulate a relatively low voltage and to provide a regulated low voltage, high current, low impedance output.

Another object of the present invention is to provide an improved voltage regulator suitable for regulating the voltage supply in a vehicle sufficiently so that it may be used to power a portable television receiver, and the like, satisfactorily.

A further object of the present invention is to provide an improved voltage regulator employing a transistor whose emitter-collector path is connected in series with an input terminal and an output terminal of the regulator, and whose bias is provided by a constant current device.

Still a further object of the present invention is to provide an improved voltage regulator employing a constant voltage device in addition to the constant current device, permitting the requirements upon both the current and the voltage regulating devices to be relaxed because of this combined regulating action.

In accordance with the present invention, the foregoing and related advantages are attained in a novel voltage regulator comprising a transistor and a constant current device to bias the transistor. The voltage to be regulated is applied between a pair of input terminals of the voltage regulator circuit. The emitter-collector path of the transistor is connected between one of a pair of input terminals and one of a pair of output terminals. A constant current device, such as a ballast regulator or a lamp having a non-linear resistance, is connected between the base and the collector of the transistor for biasing purposes. The remaining input and output terminals are connected to each other. If low impedance output of the voltage regulator is desired, a resistor of relatively low resistance or a constant voltage device is connected between the base of the transistor and one of the output terminals.

The novel features of the present invention, as well as the invention itself, both as to its organization and methods of operation, will be understood in detail when considered in connection with the accompanying drawing, in which similar reference characters represent similar parts, and in which:

FIG. 1 is a schematic diagram, partly in block diagram form, of an improved voltage regulator, in accordance with the present invention; and

2

FIG. 2 is a schematic diagram of a modification of the improved voltage regulator.

Referring now to FIG. 1, there is shown an improved voltage regulator 10 having a positive input terminal 12 and a negative input terminal 14. A voltage V_{in} to be regulated is applied across the input terminals 12 and 14. The voltage regulator 10 has a positive output terminal 16 and a negative output terminal 18 for applying a load 19 therebetween, whereby to receive a regulated voltage 10 V_{out} .

A transistor 20, shown here as a PNP transistor, has an emitter connected to the negative output terminal 18, and a collector connected to the negative input terminal 14. A constant current device 22 is used to bias the transistor 20. The constant current device may comprise a non-linear resistance having a positive voltage coefficient of resistance, such as a ballast regulator or an ordinary lamp. It will be understood that, by the term constant current device, as used herein and in the appended claims, is meant an impedance through which the current variations are relatively smaller than the voltage variations across the device. A lamp, for example, whose resistance varies directly with the voltage across it, is such a non-linear impedance as may be considered a constant current device within the scope of the instant invention, since the current through the lamp will remain substantially constant over a relatively wide range of voltages impressed across the lamp.

The operation of the voltage regulator 10, thus far described in FIG. 1, will now be explained. Let it be assumed that the voltage V_{in} to be regulated has a tendency to increase. This increase in voltage will tend to increase the current through the load 19. It is a well-known fact, however, that the current flowing through the emitter of a transistor is equal to

$$I_e = kI_b$$

where I_e is the current through the emitter, I_b is the current through the base, and k is the emitter to base current gain of the transistor.

Since the current through the base is maintained constant by the constant current device 22, the current through the load 19, between the output terminals 16 and 18, will also remain constant. The voltage across the load 19 will, therefore, remain substantially constant. It will be understood, also, that a tendency for the unregulated voltage V_{in} to decrease will not affect the substantially constant emitter current, and the voltage across the load 19 will remain substantially constant.

If it is desired to have a low output impedance voltage regulator, making the output voltage V_{out} independent of any changes in the impedance of the load 19, an impedance 24, such as a resistor, is connected between the base of the transistor 20 and the positive output terminal 16. Looking back from the output terminals 16 and 18, an effective impedance appears equal to impedance 24 divided by the current gain, k , of the transistor 20. This effective impedance may be made low with respect to the impedance of the load 19 without causing an excessive current flow compared to the load current by virtue of the fact that the actual impedance 24 is k times the impedance that is reflected to the output terminals 16 and 18.

Referring, now, to FIG. 2, there is shown a voltage regulator 30, in accordance with the present invention, wherein the constant current device comprises a lamp 32 connected between the base and the collector of the transistor 20. An impedance having a constant voltage characteristic, such as a zener diode 34, has its anode connected between the base of the transistor 20 and its cathode connected to the positive output terminal 16.

The operation of the voltage regulator 30 of FIG. 2 will now be explained. If the constant current device 32

is an imperfect device, such as a GE40 or GE47 bulb, in that some current variations will occur for variations in the unregulated input voltage V_{in} , then a voltage variation will occur between the base of the transistor 20 and the output terminal 16 if the diode 34 were omitted. This voltage variation would also be across the load 19. This voltage variation, although smaller than would be the case if element 32 were a linear resistor, may be too high for certain applications. With the zener diode 34 connected as shown in FIG. 2, the voltage across its terminals, and hence the output, will remain essentially constant. It should be noted that the use of the constant voltage device 34 has relaxed the requirements upon the constant current device, lamp 32, for a given amount of regulation. It should also be noted that the constant current device 32 will reduce the variations in the current in the constant voltage device, diode 34, thereby relaxing the requirements upon the latter device. Thus, the two devices, lamp 32 and diode 34, cooperate to give better regulation against changes in input voltage than would obtain with either device used by itself.

The constant voltage device, diode 34, has a very low dynamic impedance and hence a low dynamic impedance is reflected across the output terminals making the output voltage independent of changes in the impedance of the load 19.

While a PNP transistor has been described and illustrated in the circuits of the present invention, it will be understood that an NPN transistor may be used if the polarities of the terminals and the zener diode are reversed.
